CONTAINER AND METHOD OF MAKING
SAMEChester M. MacChesney, Chicago, Ill., assignor to
Acme Steel Company, Chicago, Ill., a corpora-
tion of Illinois

Application February 5, 1932, Serial No. 591,081

3 Claims. (Cl. 217—89)

This invention relates to improvements in containers such as candy pails, butter tubs and the like, and its purpose is to provide an improved container having novel means for attaching the cover to the vessel and an improved method by which an interlocking connection between the cover and the vessel is established.

Candy pails, butter tubs and the like have heretofore usually been made of wood with outer walls formed of upwardly flaring staves held in assembled relation by surrounding hoops or bands and the top covers of these containers have also been formed of wood and have usually been attached to the lower vessel portion of the container by means of metal cleats or by means of wooden rims or the like. Such fastening means have been found insecure with the result that the covers have frequently become loose from the vessels during shipment and efforts have therefore been made to provide improved containers having metallic rims surrounding the edge of the cover and secured to the vessel. The principal object of the present invention is to provide an improved container having a cover bounded by an annular metallic rim which is provided with means for forming a novel interlocking connection with one of the hoops or bands by which the staves of the vessel are held in assembled relation. A further object of the invention is to provide an improved method of forming a container according to which a metallic band is placed over the cover to extend downwardly around the upper part of the vessel after which the lower portion of the rim is bent inwardly to underlie the lower edge of one of the hoops or bands which surround the vessel. A further object is to provide a vessel having a surrounding hoop or band located in predetermined position so that a metallic rim carried by a cover and extending downwardly over the upper edge of the vessel may be bent inwardly to have a predetermined interlocking connection with a shoulder on the hoop or band. Other objects relate to various features of construction and arrangement and details of the method which will appear more fully hereinafter.

The nature of the invention will be understood from the following specification taken with the accompanying drawings, in which three forms of the improved container is illustrated in connection with the explanation of one example of the improved method.

In the drawings,

Fig. 1 shows a perspective view of an elong-

gated metal band which is adapted to form the annular rim of the container cover;

Fig. 2 is an enlarged perspective view of a portion of the band after the upper and lower edges thereof have been transversely corrugated; 60

Fig. 3 shows a perspective view of the rim which is formed from the band illustrated in Fig. 2 by uniting the ends thereof and bending the upper corrugated edge inwardly to form a transverse annular flange; 65

Fig. 4 shows a transverse section through the edge of the cover with a side elevation of an upper edge portion of the vessel after the rim has been applied to the cover in readiness for the application of the cover to the vessel; 70

Fig. 5 is a transverse radial section through the upper edge of the container and cover after the cover has been applied and the lower edge of the rim has been bent inwardly to form an interlocking connection with an annular wire hoop on 75 the vessel;

Fig. 6 is a perspective view of the container after the cover has been applied thereto and the rim bent into interlocking engagement with the uppermost hoop; 80

Fig. 7 is a transverse radial section similar to that of Fig. 5, showing a modified form of the invention; and

Fig. 8 is a transverse radial section similar to that of Fig. 5, showing another modification of 85 the invention.

In Fig. 1 of the drawings there is illustrated a long, narrow band of sheet metal 10 which is adapted to be operated upon to form the annular rim which surrounds the cover of the vessel. After 90 cutting the metal band 10, it is operated upon by suitable dies or the like to form the band illustrated in Fig. 2, having a central smooth portion 10^a bounded along its upper edge by a series of transverse corrugations 10^b, and along its lower edge by another series of transverse corrugations 10^c. The corrugations 10^c may preferably be of lesser length, measured transversely of the band, than the corrugations 10^b. After having formed the band as illustrated in Fig. 2, the upper transversely corrugated portion 10^b is bent transversely to form a flange 11 and the ends of the band are overlapped and united by rivets or other fastening means 12. The transverse bending of the corrugated portion 10^b may take place 105 either before or after the ends of the band are united to form the rim 13 of circular form illustrated in Fig. 3 but, in either case, the transverse corrugations accommodate themselves to the bending of the band into circular form and 110

take up the necessary contraction in the metal which is brought about by causing the parts to assume the form of a circular rim.

Having formed the rim 13 as illustrated in Fig. 3, the next step in the process of forming the container is to apply this rim to the circular cover 14 which is preferably made of wood and which is preferably provided around its upper edge surface with an annular recess 14^a. The rim 13 is passed over the cover 14 with the body portion 10^a closely engaging the annular edge surface of the cover, until the inwardly directed flange 11 seats upon the surface of the recess 14^a, as shown in Fig. 4. The cover is then passed downwardly over the top edge of the vessel 15 which is provided with a plurality of surrounding hoops or bands 16 between the upper and lower edges thereof and also with a band 17 around its extreme lower edge. The outer wall of this vessel is made up of a plurality of staves 18 which are held in assembled relation by the hoops 16 and, in this embodiment, the hoops 16 are made up of circular wire. The uppermost hoop 16 is preferably seated in an annular groove 19 which is formed in the outer surfaces of the staves adjacent their upper ends. The lower wall of this groove is preferably downwardly inclined as shown at 19^a, leaving an annular space beneath the lower edge of the uppermost hoop 16. When the cover 14 is placed in position on the upper ends of the staves as shown in Fig. 5, the rim 13 extends downwardly over the upper ends of the staves with the lower corrugated portion 10^c projecting beyond the upper hoop 16. This corrugated portion 10^c is then bent inwardly to form an annular transverse flange 20 which underlies the hoop 16 and thus holds the cover securely in position on the vessel. The transverse corrugations 10^c permit this inward bending of the lower edge of the rim without distorting the metal, since the necessary contraction is taken up in the adjustment of the corrugations to the decreased diameter of the inner edge of the flange 20.

In Fig. 7 of the drawings there is illustrated a modified form of the invention in which the container 25 is made up of a plurality of upwardly flaring staves which are held in assembled relation, adjacent their upper ends, by a surrounding hoop 26 made of sheet metal and adapted to cooperate with an inwardly formed annular groove 25^a which is formed in the wall of the container. This metal hoop has an annular outwardly projecting bead 26^a along the lower edge thereof and at a point just above its middle part it is provided with an annular inwardly extending bead or projection or corrugation 26^b which seats in the annular groove 25^a formed in the vessel. The upper wall of the corrugation 26^b is directed outwardly and inclined upwardly to a slight extent to unite with the outwardly directed corrugation or projection 26^c which extends around the hoop and unites with the upper edge portion 26^d of the hoop which lies in contact with the outer surfaces of the staves which form the container. The inwardly extending corrugation or projection 26^b holds the hoop 26 in a predetermined position on the container and the part of the hoop which extends outwardly from the corrugation 26^b to the corrugation 26^c forms an annular shoulder 26^e adapted to coact with the part of the rim which extends around the cover.

In the construction shown in Fig. 7, the cover 27 is made of wood or other suitable material and lies upon the upper edge surfaces of the staves 75 which form the container 25. This cover is pref-

erably provided with an annular recess 27^a around its upper edge surface and this recess is adapted to receive an inwardly extending transversely corrugated flange 28^a which is formed upon the metallic rim 28. The central portion 28^b of this rim is uncorrugated but it is provided at its lower edge with a transversely corrugated portion 28^c normally extending downwardly as shown by dotted lines to permit the rim to be passed downwardly over the projection 26^c of the hoop. After the rim has been passed downwardly to this position, the corrugated part 28^c is bent inwardly to form a flange 29 which coacts with the shoulder 26^e and thus maintains the cover in position on the vessel. By means of this modification, the lower edge of the rim may be bent inwardly to engage a part of a hoop which is formed of sheet metal and which has considerable width. The rim 28 is formed as in the first embodiment of the invention by providing an elongated strip of metal with two series of transverse corrugations along its edges after which the upper series of corrugations are bent transversely to form the flange 28^a before the parts are assembled on the container 25.

In Fig. 8 of the drawings there is shown another modification of the invention which permits the application of the rim to a hoop formed of sheet metal. In this form, the container 30 is formed of upwardly flaring staves which are held in assembled relation adjacent their upper extremities by the surrounding metal hoop 31. This hoop is formed of sheet metal which is bent to form two beads 31^a and 31^b on its upper and lower edges, respectively. Between these beads, the hoop is provided with an inwardly extending projection or corrugation 31^c which is adapted to snap into engagement with an annular groove 30^a formed in the wall of the container when the hoop is driven upwardly over the flaring staves. The engagement of this corrugation 31^c with the groove in the container thus holds the hoop in a predetermined position with respect to the upper edge of the container on which the circular cover 32 is adapted to seat. This cover is provided with an annular recess 32^a around its upper edge and this recess is engaged by an inwardly extending transversely corrugated flange 33^a formed on the upper edge of a metallic rim 33. This rim is provided at its lower edge with a transversely corrugated inwardly extending flange 33^b which underlies the bead 31^a formed on the upper edge of the hoop for the purpose of holding the rim and cover in fixed positions with respect to the container 30. In forming the rim 33, an elongated metal band is first provided with two series of transverse corrugations along its edges after which the band has its ends united to form an annular rim and the upper series of corrugations are bent inwardly to form the flange 33^a. The annular rim is then passed downwardly over the cover 32 with the lower corrugated portion extending beyond the upper bead 31^a. This lower corrugated portion is then bent inwardly to form the lower transverse flange 33^b engaging the under side of the bead 31^a.

The subject-matter of the present invention is claimed broadly in applicant's co-pending application Serial No. 538,094, filed May 18, 1931.

Although three forms of the invention have been illustrated and described in connection with the explanation of one example of the improved method, it will be understood that the container may be made in various forms and by various

modifications of the improved method coming within the scope of the appended claims.

I claim:

- 5 1. A container comprising a vessel having an annular recess therein adjacent its upper edge, an annular hoop having a part engaging said recess and having an outwardly extending annular shoulder, a cover for said vessel, and a sheet metal rim having an annular transversely corrugated flange overlying a part of said cover and having another inwardly extending transversely corrugated flange underlying said shoulder.
- 10 2. The method of forming a container which consists in providing a vessel with an annular groove in its outer surface adjacent its upper edge, placing around said vessel a hoop having a part engaging said groove and having an outwardly extending shoulder, placing a cover on said vessel, forming an annular metallic rim with two
- 15 20 series of transverse corrugations along its edges,

bending one of said series of transverse corrugations inwardly to form an upper inwardly extending flange, placing said rim over said cover with said flange overlying said cover, and then bending said other series of corrugations inwardly to form a flange underlying said shoulder on said hoop.

3. A container comprising a vessel having an annular recess therein adjacent its upper edge, an annular sheet metal hoop surrounding said vessel and having an inwardly extending annular bead engaging said recess, said hoop being provided further with an outwardly extending annular bead, a cover seated on said vessel, and an annular metallic rim having a part overlying said cover and having the lower annular edge portion thereof transversely corrugated to permit the bending of this portion inwardly beneath said last-named bead.
